(57) **CLAIM**

The ornamental appearance of a headgear, as shown and described.

DESCRIPTION

The sole FIGURE is a front elevation view of headgear showing our new design in a flat condition.

The thickness of the headgear forms no part of the claimed design.

The broken lines showing environment or structure of the headgear are for illustrative purposes only and form no part of the claimed design. The dotted lines represent the border between claimed and non-claimed subject matter and form no part of the claimed design.
